UNITED STATES PATENT OFFICE

RANDOLPH BOYD, OF GALVA, ILLINOIS

BELT BUCKLE

Application filed September 30, 1929. Serial No. 396,345.

This invention has reference to belt buckles for personal use, the primary object of the invention being to provide a belt buckle which will prevent sagging of the belt under the weight of the buckle.

Another object of the invention is to provide a buckle which will hold the belt flat and prevent curling of the belt at the free end thereof.

10 A still further object of the invention is the provision of a detachable belt buckle which may be readily and easily removed for transferring the buckle from one belt to another.

With the foregoing and other objects in view, which will appear as the description proceeds, the invention resides in the combination and arrangement of parts and in the details of construction hereinafter described and claimed, it being understood that changes 20 in the precise embodiment of the invention herein disclosed, may be made within the scope of what is claimed, without departing from the spirit of the invention.

Referring to the drawings:

25 Figure 1 is a plan view of a buckle constructed in accordance with the invention.

Figure 2 is a bottom plan view thereof.

Figure 3 is a longitudinal sectional view through the buckle.

30 Figure 4 is a sectional view taken on line 4—4 of Figure 2.

Referring to the drawings in detail, the buckle includes an elongated body portion indicated generally by the reference character 35 5, the same being hollow, defining an inner wall 6 and an outer wall 7. The wall 6 is formed with a substantially T shaped cut out portion providing an opening 8 and an opening 9, the opening 8 being designed to 40 permit one end of the belt, which is indicated by the reference character 10, to be passed therethrough and positioned over the tongue, which is indicated by the reference character 11.

45 An opening 12 is formed in the wall 6 through which one end of the tongue 11 extends, the tongue 11 being shown as bent around that portion of the wall 6 adjacent to the openings 8 and 12, to pivotally secure the 50 tongue to the buckle. A wide opening 13 is

formed in the outer wall 7 of the buckle, through which opening the free end of the tongue 11 extends, the free end of the tongue being curved to fit into a curved recess formed in the outer surface of the wall 7, to prevent 55 lateral movement of the tongue.

The cut out portion 13 also permits a portion of the belt to be exposed, lending a pleasing appearance to the belt and buckle.

It is of course understood that the body 60 portion is slightly curved to conform to the shape of the body, and that the ends of the buckle are open to permit the belt to be passed therethrough, in a manner as shown by the drawings.

65 From the foregoing, it will be obvious that the buckle will house portions of the belt and prevent the belt from sagging under the weight of the buckle, when the belt is worn with other trousers supporting means, such 70 as suspenders or the like.

I claim:

In a belt, a buckle embodying an elongated body portion having spaced outer and inner walls, the outer wall being cut away providing a tongue opening, a tongue pivotally connected with the inner wall and extending through the cut away portion, one end of the belt extending into the buckle, through one end thereof and having an opening to receive 80 the tongue near the base of the tongue, to secure said end of the belt to the buckle, and the opposite end of the belt being passed through the buckle from the opposite end 85 of the buckle, and the latter end of the belt having an opening to receive the tongue.

In testimony that I claim the foregoing as my own, I have hereto affixed my signature.

RANDOLPH BOYD.
